UNITED STATES PATENT OFFICE.

DANIEL J. McCARTHY, OF WILKINSBURG, PENNSYLVANIA, ASSIGNOR TO UNION SWITCH & SIGNAL COMPANY, OF SWISSVALE, PENNSYLVANIA, A CORPORATION OF PENNSYLVANIA.

SIGNAL SYSTEM WITH CONTINUOUS RAIL CONNECTIONS.

No. 907,165.

Specification of Letters Patent.

Patented Dec. 22, 1908.

Application filed April 25, 1907. Serial No. 370,230.

To all whom it may concern:

Be it known that I, DANIEL J. McCARTHY, of Wilkinsburg, Allegheny county, Pennsylvania, have invented a new and useful 5 Signal System with Continuous Rail Connections, of which the following is a full, clear, and exact description, reference being had to the accompanying drawings, forming part of this specification, in which the 10 figure is a diagrammatic plan view showing a portion of a railway-track constructed in accordance with my invention.

The invention relates to block signaling, and is designed to do away with the use of 15 insulated joints and impedance bonds. In my system the rails are in continuous electric connection with each other, and the impedance of the rails is utilized by connecting transformers to successive portions of 20 the track, two transformers being used with one relay to operate a signal protecting a certain portion of the track.

In the drawings, 2 represents an alternating current generator supplying current 25 to the line 3 which energizes transformers 4, 5 and 6. The secondaries of these transformers are connected to the track rails 7 and 8, to which are connected the relays 9, 10, etc. These relays are connected to 30 the rails at points about midway between the transformer connections; and the voltage of the secondaries of the transformers is made such that the combined action of 35 two transformers, such as 5 and 6 is of the proper value for furnishing the necessary amount of current to relay 10 for its operation. If the rails are short circuited by a train at any point between 4 and 5, the relay 9 will be shunted, thus opening the local 40 circuit 11 to signal 12, causing it to indicate a danger condition. As the train passes from between transformers 4 and 5 to the successive portion of track between transformers 5 and 6, the relay 10 will be operated, 45 thus opening the local circuit 13 to signal 14 which will then assume a danger position. As the impedance builds up back of the train, the relay 9 will be operated to bring the signal 12 to clear. These operations take 50 place successively as the train moves along the track.

The advantages of my invention result from doing away with the track sections with insulating joints and impedance coils; by impressing currents upon successive 55 portions of the track, and using two transformers to operate a relay controlling the signal which protects such portion. The system is simple and not liable to get out of order, and only one frequency of current 60 need be employed.

The system may be employed for electric roads using either direct current or alternating current, the alternating current being of 65 a different frequency from that for the signal system; or the system may be applied to steam roads or roads having other power for propulsion.

Other variations may be made in the form and arrangement of the device and their connections without departing from my invention.

I claim:

1. A railroad having the rails in continuous electric connection, a signal system having signals each connected to one relay only, and two transformers each of the same phase and each arranged to supply current through the track to said relay, either one of said 75 transformers supplying insufficient current 80 to operate the relay; substantially as described.

2. A railroad having rails in continuous electric connection, a signal system having signals each connected to and operated by 85 one relay only, and two transformers supplying currents of the same frequency in the same phase to said relay, each of the transformers supplying an insufficient current to 90 operate said relay; substantially as described.

3. A railroad having the rails in continuous electrical connection, a signal system having signals each connected to one relay only, and two transformers each of which is arranged to supply current through the track 95 rails to said relay either one of said transformers alone supplying insufficient current to operate the relay, substantially as described.

4. A railroad having the rails in continuous electrical connection, a signal system having signals each connected to one relay

only, and two transformers each of which is arranged to supply current through the track rails to said relay, either one of said transformers alone supplying insufficient current to operate the relay, and each transformer supplying current to relays controlling two different signals; substantially as described.

In testimony whereof, I have hereunto set my hand.

DANIEL J. McCARTHY.
